UNITED STATES PATENT OFFICE.

ESPIRIDION HIPOLITO, OF LOS ANGELES, CALIFORNIA.

PIVOTED WINDOW.

SPECIFICATION forming part of Letters Patent No. 740,015, dated September 29, 1903.

Application filed December 26, 1900. Serial No. 41,145. (No model.)

To all whom it may concern:

Be it known that I, ESPIRIDION HIPOLITO, a citizen of the United States, residing at Los Angeles, in the county of Los Angeles and 5 State of California, have invented new and useful Improvements in Pivoted Windows, of which the following is a specification.

The object of my present invention is to provide a pivoted window of cheaper, more 10 compact, and more convenient construction and assemblage and of more convenient operation than pivoted windows heretofore known.

An object of this invention is to avoid all 15 need of mortising and to fit the parts in the sash by means of a saw and boring-bit only.

In my former application, Serial No. 18,459, filed in the United States Patent Office May 29, 1900, I have shown a sash-body provided 20 in its edge with a groove, a pivot member fastened to the sash-body and extending outward from the bottom of the groove, a tongue mounted in the groove and provided with a hole and fitted to slide upon the stem of the 25 pivot member, a bar on the grooved edge of the sash-body and provided with a groove to face the groove of the sash-body, a socket member fastened to the bar and provided with a socket to receive the stem of the pivot 30 member, a screw screwed through the socket member and into the pivot member, and means for moving the tongue across and retracting it from the plane of the contacting faces of the bar and the sash-body. In my 35 present application I employ the above-described construction.

I do not herein make any claim broadly to 40 said construction, for the reason that it is claimed in said former application.

My present invention relates to improvements by means of which the operation of the window is brought positively under the control of the operator. In the present invention I furnish each window-sash with means 45 whereby the operator can positively adjust the tongues in position for holding the window against turning on its pivots and can also adjust the tongues in position fully withdrawn within the stile to allow the window to turn 50 on its pivots. In some embodiments of my invention in order to cause the respective tongues to safely remain in each of the dif-

ferent positions to which they may be adjusted I have found it desirable to provide resilient devices frictionally engaging the sides of 55 said tongues.

My invention is capable of being carried out in various ways, and in the accompanying drawings I have shown four methods of carrying out the invention. In my present invention I adjust each of the tongues by means fastened to the tongue and extending through the stile of the sash for the purpose of moving the tongue positively into and out of the groove in the stile and retaining it positively 60 in position at the pleasure of the operator. This means comprises two draw bars or rods for each of the tongues, respectively, said draw bars or rods being fastened to the tongue and extending into the stile of the sash. The 65 draw bars or rods may extend through the stile, or the extension thereof may be made by suitable connections which can be handled to operate the tongue from the inner face or the inner edge of the stile, as the case may be, as 70 illustrated in the accompanying drawings. My invention also pertains to the construction 75 of the window-frame.

Figure I is a fragmental elevation of a window embodying my invention. Parts are 80 broken to expose interior parts. Fig. II is a section, on an enlarged scale, on line III III, Fig. I. Fig. III is a section on line indicated by III III, Fig. II, showing a crank-shaft screwed directly into the wooden member of the sash. 85 Fig. IV is a fragmental sectional elevation showing a modified form of my invention. IV IV, Fig. V, shows the plane of section. Fig. V is a fragmental plan section on line V V, Fig. IV. Fig. VI is a fragmental view 90 showing my invention applied in another form. Fig. VII is a section on line VII VII, Fig. VI. Fig. VIII is a section on line VIII VIII, Fig. VI. Fig. IX is a view of a still further modification of the invention, in 95 which two turning members are provided, one connected with the upper ends of the two tongues and the other connected with the lower ends of said tongues. Fig. X is a section across one side of the window frame 100 and sash.

a indicates a window-sash body furnished with grooves *b b* in two opposite edges of said body.

c indicates a grooved bar or sash-carrying strip, the grooved face of which is applied to one of the grooved edges of the body *a*. The grooved bar *c* is mounted with its grooves *d* facing the groove *b* of the sash-body edge to which said bar is applied.

e indicates a tongue for the way formed by the conjoined grooves *d* and *b* of the grooved edge formed by stile *l* and the bar *c*. In a general way *f* indicates the pivot through the tongue *e* and pivoting the bar *c* and the grooved edge or stile *l* together. *e'* indicates another tongue mounted in the other side of the sash-body and in the grooved bar or sash-carrying strip, the grooved face of which is applied to the other of said grooved edges—viz., stile *l'*. The opposite edges of the sash are correspondingly constructed.

g indicates a draw bar or rod in the form of a link fastened, by means of a pivot *h*, to the tongue *e* to move said tongue at a right angle to the grooves in the sash. The links or rods *g* extend into the sash-stile *l* from the bottom of the groove *b* thereof. Preferably two draw-bars are provided for each tongue, and they are arranged on opposite sides of and equidistant from the pivot. Suitable positive means are furnished for operating the links and constitute virtual extensions of the links or draw-bars, which are connected with the tongue. In the form shown in Figs. I, II, and III a short shaft *i* is set into the sash, preferably flush therewith and at right angles to the link *g*, and is furnished at its inner end with a wrist-pin *j*, which is preferably integral with the shaft and is inserted through a hole *g'* in the link *g*. The shaft *i* is preferably in the form of a cylindrical plug, which is screw-threaded throughout a portion of its body, as indicated at *i'*, and is furnished with means, such as the slot *i''*, by which it may be turned. Preferably an internally-screw-threaded metal sleeve *k* is furnished, the same being driven into a hole bored into the sash to receive the same. The screw-threads *i'* of the shaft *i*, (shown in Fig. II,) however, may be screwed directly into the wood, as suggested in Fig. III, from which the sleeve *k* is omitted. A link *g* and shaft *i* therefor is preferably provided near each end of the tongue, so that by appropriately turning the shaft *i* the crank-pin *j* will operate the link to force the tongue out or in, as may be desired.

In Figs. IV and V the link *g* is pivoted to a lever *m*, which is pivoted by a pivot *n* to the stile of the sash-body, which stile is provided with a recess *o*, and the lever projects into the recess when otherwise fully chambered in the sash-stile, thus enabling the user to operate the lever to withdraw the tongue from the groove in the bar *c*.

With the form shown in Figs. I, II, and III when the operator wishes to swing the window on its pivot he will, by means of a screw-driver or other appropriate instrument, appropriately turn the several shafts *i* to

withdraw the tongues from the pivoted sliding bars. Then the window is free to be turned on its pivots. When it is desired to again fasten the window in upright position, the window will be brought into appropriate position and the shafts *i* turned to throw the tongues into their respective bars or sash-carrying strips.

In the form shown in Figs. IV and V when the window is unlocked the operator who wishes to turn the sash on its pivot will first draw the free ends of the levers *m*, (two being provided for each stile,) and will thus withdraw the tongues from their respective grooves and allow the window to be turned. By the reverse operation the window will be again secured in place.

The form shown in Figs. VI, VII, and VIII is the simplest and in some respects the most desirable form of my invention. In this form the draw bars or rods *g'* are screws which are screwed into the tongues and extend through the stiles *l l'*, respectively, of the sash. Two draw-bars *g'* are provided for each of the tongues *e''* and are screwed directly into the tongues *e''*. *p* indicates U-shaped springs which are seated in the sash-grooves *b* to frictionally engage the tongues pertaining to the stiles, respectively. The purpose of these springs is to hold the tongues friction-tight in different edgewise positions in their respective grooves *b*. These springs are especially desirable for the form of my invention shown in Figs. VI, VII, and VIII, but may be applied or omitted in any of the forms shown in the drawings.

With the form shown in Figs. VI, VII, and VIII the operator who desires to turn the sash upon its pivots will take hold of the heads of the screws *g'*, pertaining to one of the tongues, and will pull upon them, thus drawing the tongues *e''*, respectively, into the grooves of the sash-stiles, respectively. When the tongues are fully seated in the sash-stiles, the sash can be readily swung upon its pivots.

q indicates tacks or brads for fastening the springs *p* in position.

In the form shown in Fig. IX the turning shafts or members *i'* are located midway of the rails at the top and bottom of the window, and each is furnished with two crank-pins *j*, arranged on opposite sides, respectively, of the shaft *i*. *g''* indicates two links or connections which are pivoted, respectively, to the crank-pins *j* and extend, respectively, through the stiles and through holes *r* in the sash-rails, respectively, and are pivoted by pivots *s* to the sash-carrying strips *e''*.

In practical operation the person desiring to turn the window on its pivots will, by means of a screw-driver or other suitable instrument, turn the shafts *i'*, thus simultaneously moving both of the connecting rods or links *g''*, and will thus draw the tongue out of its locked position, so that the sash and the frame are connected solely by the pivotal device. When the tongue is fully seated in the

grooves in the sash, said sash may be freely turned in any direction, the tongue being retained out of the way and entirely protected from injury and prevented from wearing off the edges of the groove in the non-pivoted members.

In the several figures, *u* indicates the window-frame, furnished with the dovetail grooves or runways *v*, in which the sash-carrying strips *c* slide. By means of this dovetail arrangement the sash-carrying strips are held firmly throughout their entire length and are prevented from springing out from the sides of the window-frame at top and bottom when the sash is swung on its pivots. The dovetail form of groove is produced by means of bevel-stops, as more particularly shown in Fig. X, in which the inside stop 12 is beveled upon the face 13, which engages the sash-carrying strip, and the outer or blind stop 14 is furnished with a bevel-groove 15, into which the bevel face 16 of the outer sash-carrying strip fits.

17 indicates the pulley-stile of the window-frame, to which the inside stop 12, the blind-stop 14, and the parting bead or stop 18 are fastened.

It is to be understood that the lower and upper sashes *a* and *a'* are pivoted to their respective sash-carrying strips *c* and *c'* in the same way and that the upper sash is to be provided with means for locking the sash to and unlocking it from its sash-carrying strips in substantially the same manner as that employed for the lower sash.

It will be seen that in all the forms of my invention shown the tongue-shifting mechanism is neat in appearance, and no portion thereof projects in a manner that might lead to its accidental displacement.

What I claim, and desire to secure by Letters Patent of the United States, is—

1. The combination of a frame furnished with runways at its sides; sash-carrying strips sliding in said runways respectively and grooved on their sash-engaging faces respectively; a sash furnished in its stiles with grooves which register with the grooves of the sash-carrying strips respectively; tongues in the grooves on the opposite sides of the sash respectively to chamber within their respective sash-grooves and to slide outward across the joint between the sash and the sash-carrying strips respectively; a pivotal connection extending through one of said tongues and connecting one sash-carrying strip with one stile of the sash; another pivotal connection extending through the other tongue and pivotally connecting the other sash-carrying strip with the other stile of the sash; tongue-operating rods fastened to the tongues respectively and extending through the sash-stiles respectively for the purpose of moving said tongues to and fro at a right angle to the grooves therefor respectively; and friction-springs in the sash-grooves respectively frictionally engaging directly upon the tongues

respectively, and adapted to retain said tongues in different edgewise positions.

2. The combination of the grooved stile; a grooved sash-carrying strip; a transversely-movable tongue in the groove adapted to slide within and at a right angle to the conjoined grooves of the stile and sash-carrying strip and adapted to chamber within the sash-groove; a pivotal connection fastened to and connecting the stile and the sash-carrying strip; tongue-operating draw-bars fastened to the tongue and extending through the stile; and springs mounted in the sash and frictionally gripping the tongue on opposite sides thereof to retain it in different edgewise positions.

3. The combination with the grooved sash and the grooved bars pivoted thereto, of a tongue mounted in the groove in the sash-body and adapted to fully seat therein and to be extended across the plane of the contacting faces of the bar into the sash-body; a link pivoted to the tongue and extending into the sash-body for the operation of the tongue; and a crank-shaft having the form of a cylindrical plug seated to rotate in the sash-body and furnished with a wrist-pin which is integral with the crank-shaft for operating the link.

4. The combination with the grooved sash and the grooved bars pivoted thereto, of a tongue mounted in the groove in the sash-body and adapted to fully seat therein and to be extended across the plane of the contacting faces of the bar into the sash-body; a link pivoted to the tongue and extending into the sash-body for the operation of the tongue; and a screw-threaded shaft screwed into the sash-body and journaled therein and furnished with a crank-pin operatively connected with the link.

5. The combination with the grooved sash and the grooved bars pivoted thereto, of a tongue mounted in the groove in the sash-body and adapted to fully seat therein and to be extended across the plane of the contacting faces of the bar into the sash-body; a link pivoted to the tongue and extending into the sash-body for the operation of the tongue; a metal sleeve in the sash-body; and a screw-threaded shaft screwed into said sleeve of the sash-body and journaled therein and furnished with a crank-pin operatively connected with the link.

6. In a window, in combination, a grooved stile, a grooved sash-carrying strip, a tongue in the groove to slide in the conjoined grooves of the stile and sash-carrying strip and adapted to chamber within the sash-groove, tongue-operating means fastened to the tongue, and a U-shaped spring frictionally gripping the tongue on opposite sides thereof and adapted to frictionally retain it in different edgewise positions.

7. The combination of a grooved sash, a tongue in the groove, a link attached to the tongue and extending into the sash-stile, a crank-shaft in the form of a screw-threaded

4

plug extending into the sash-body and flush therewith, said crank-shaft being furnished with means at one end for turning it and a wrist-pin integral therewith at the other end, 5 said wrist-pin being operatively connected with the link.

In testimony whereof I have signed my

name to this specification, in the presence of two subscribing witnesses, at Los Angeles, California, this 15th day of December, 1900.

ESPIRIDION HIPOLITO.
